METHOD OF AND MECHANISM FOR FEEDING FOLDED SHEETS TO SHEET OPENING DEVICES IN A SHEET-HANDLING MACHINE

Oscar Kleinschmit and Rudolf Klemm, Leipzig-Plagwitz, Germany, assignors to Gebruder Brehmer, Leipzig-Plagwitz, Germany, a limited partnership of Germany

Application January 21, 1932, Serial No. 588,002
In Germany February 9, 1931

17 Claims. (Cl. 271—74)

This invention relates to sheet-handling machines (e. g. book-binding or stitching machines) in which inversely rotating suction members are utilized to open single or multiple folded sheets.

When such sheet opening devices are employed, the folded sheet to be opened is fed to the rolls or similar suction members with the open edges, which are parallel to the fold thereof, foremost. These edges are then caused to enter between the suction members so that the said open edges are parallel to the axes of rotation of the suction members and are thereupon seized and opened simultaneously along the whole length of the open edges. In practice it has been found that by thus simultaneously parting these edges of the sheet, certain disadvantages are experienced, more particularly when the folded sheets are formed from thin material.

According to the method of this invention to obviate these disadvantages a folded sheet or book section is fed to sheet opening members so that the leaves of the said sheet are initially parted from one corner thereof.

In order to carry this invention into effect, a sheet conveyor, such as the usual conveyor tapes, may be provided to convey the folded sheet to the inversely rotating suction members. A series of pivotally mounted fingers or sheet stops may be arranged to project into the path of travel of the folded sheet as the latter is conveyed by the conveyor tapes, and the stops so arranged are positioned in a line at an angle to the direction of travel of the folded sheet. The pivoted stops may be moved about their axes by suitably timed mechanism co-operating with the drive of the machine so that the stops are caused to engage and then release the sheet to allow the latter at the requisite moment to enter between the sheet opening members. When retarded in its travel, by the interposed stops the sheet, by reason of the still moving conveyor tapes, is swung out of its straight path of travel so that the front open edges thereof abut the oblique line of stops. A series of rubber faced or similar rollers are suspended by pivotal arms above the conveyor tapes and associated with the sheet stops so that when the latter are removed from the path of the sheet, the rollers are caused to engage the surface of the said sheet and so hold it in the oblique position, relatively to the conveyor tapes during the remainder of its travel towards the sheet-opening members.

Held thus, between the conveyor tapes and the upper rollers, the sheet is caused to enter

with one open corner foremost between the inversely rotating members. In this manner, the sheet is opened, as is desirable, from one open corner with the line of parting extending across the folded sheet at an angle to the open front edge thereof.

One specific constructional form of this invention will now be described in reference to the accompanying drawings in which:

Fig. 1 is a fragmentary side elevational view of a sheet handling machine provided with the sheet opening device according to this invention.

Fig. 2 is a detail plan view showing the sheet conveyor tapes and obliquely set sheet-stops.

Fig. 3 is a diagrammatic elevational view showing the position of the sheet according to this invention when about to enter between the inversely rotating suction rolls, and

Fig. 4 is a perspective view of a folded sheet showing the manner of opening according to this invention.

Referring to Fig. 1, the machine frame 10 supports a stack container 11 which receives a stack of folded sheets or book sections A. The front closure of the stack container 11 may comprise a slidable rake member 12 which is slotted as at 13 and in association with pivotal sucker members 14 and retaining fingers 15 serves to separate individually the constituents of the stack.

A pair of inversely rotating suction rolls 16, 17 (Figs. 1 and 3) are mounted on driven shafts 18, 19 journaled in the machine frame 10. The suction rolls, arranged horizontally, are adapted to receive and open one by one the folded sheets as the latter are separated from the stack and the means for conveying the separated sheets to the suction rolls are as follows:

Conveyor pulleys or rollers 16', 17' of diameter equal to that of the suction rolls are mounted on the shafts 18, 19 respectively. Similar conveyor pulleys 20 of smaller diameter and equivalent in number to the pulleys 16', 17' are mounted on a shaft journaled beneath the stack container 11 in the machine frame 10. Endless conveyor tapes 21 are passed around the pulleys 17' and 20 and also a series of guiding pulleys 22, 23 mounted on shafts journaled in the machine frame 10, while tensioning pulleys 24 pivotally supported in the machine frame are adapted to engage and tension the conveyor tapes 21. The latter thus extend from the suction roll 17 to beneath the stack container 11 so that the sheets separated from the stack are deposited thereon.

A second series of endless conveyor tapes 25 are passed around the pulleys 16' and three se-

ries of similar pulleys 26, 27 and 28 which are mounted on shafts journaled in the machine frame, the pulleys 28 being positioned so that the portions of the conveyor tapes 25 which extend between the pulleys 16' and 28 are each closely adjacent the corresponding conveyor tape 21 in order that the sheets passing between the tapes at this point are gripped thereby and fed in a set position to the suction rolls 16, 17.

10 Intermediate the upper run or sheet receiving portion of the conveyor tapes 21 a series of rotatable idler rollers 29 are arranged to engage from below the tapes 21. A series of preferably rubber faced drop feed rollers 30 are rotatably mounted in arms 31 all of which are fixedly mounted on a common rock shaft 32 mounted in the frame of the machine. The arms 31 are shaped so that when lowered the rollers 30 contact with the tapes 21 and register with the corresponding rollers 29 thus providing means for gripping and positively feeding forward the sheet positioned therebetween. A two-armed rocking lever 33 is fixedly mounted on the rock shaft 32 and one arm thereof, through a pivoted bell-crank lever 34 and connecting rods 35, 36, is linked to a fulcrumed two-arm lever 37 which carries a cam follower adapted to engage a timing cam mounted on the driving shaft 38 of the machine.

15 A series of sheet stops 39, associated with the rollers 29, 30, are secured to curved arms 40 which are fixedly mounted upon a rock shaft 41 the latter being journaled in suitable brackets mounted on the machine frame 10. An arm 42 rigidly mounted on the rock shaft 41 is linked by a connecting rod 43 to the second arm of the rocking lever 33. The stops 39 are set in a line obliquely to the axis of rotation of the suction rolls 16, 17, that is to say obliquely to the longitudinal direction of the conveyor tapes and the arrangement of the above described actuating linkage is such that when the drop feed rolls 30 are lifted from the tapes 21 the stops 39 are caused to project between the tapes 21 into the path of the travelling sheet.

20 The suction rolls 16, 17 and conveyor tapes 21, 25 are constantly driven from the drive shaft 38 through the interposed gear train B.

25 The operation of the sheet feeding and opening device is as follows:

30 The folded sheet S, when separated from the stack A by the means above mentioned, is deposited upon the constantly driven conveyor tapes 21 with the open edges which are parallel to the fold thereof, foremost. The constantly driven conveyor tapes 21 then convey the sheet S forward and towards the sheet-stops 39 which are timed to project, at this juncture of the operation, into the path of travel of the sheet S. In due course the forward open edges of the sheet abut the stops 39 and in consequence of the obliquity of the latter the sheet is swung about on the tapes 21 to the position shown in Fig. 2.

35 The continued movement of the drive shaft 38 and cam actuated linkage above described then withdraws the sheet-stops from the path of the now obliquely positioned sheet and simultaneously the drop feed rollers 30 descend and engage between them and the tapes 21 and rollers 29 the sheet S. The latter is thus held in its obliquely set position and carried forward to the superposed gripper conveyor tapes 25 whereupon the sheet is gripped between the tapes 21 and 25 and so presented to the suction rolls 16, 17 in the position shown in Fig. 3. Consequently the corner x

of the sheet is gripped first between the suction rolls and the sheet is opened obliquely to its folded edge on a line approximately as indicated by the chain-dotted line I—I (Fig. 3) and shown in Fig. 4. The sheet so passes through the suction rolls and is deposited in its opened condition upon a suitable conveying saddle not shown.

35 As will be readily understood by those skilled in the art, it is highly advantageous to open mechanically a folded sheet in this manner since it obviates the wrinkling and crumpling of the leaves which often occurs when squarely parting the leaves of a folded sheet owing to the natural mutual adhesion thereof.

40 Many forms of mechanism may be devised for carrying the invention into effect and such mechanism could be operated from above, below or laterally of the machine according to the position of the sheet conveyor. The invention is not confined to the specific construction above described and may be incorporated in any sheet-handling machine in which rotatable sheet opening members are used.

45 While the use of stops for ensuring the obliquity of the folded sheet relative to the opening members has been described, it will be clear that such obliquity may be obtained by suitable location of the mechanism. Thus, the opening members, conveyor, or sheet stack may be placed at a suitable angle relatively to the other parts of the mechanism or alternatively an oblique side guide provided for the sheet and a cross moving conveyor belt or belts arranged to engage the sheet and so swing it from the longitudinally parallel path of travel as desired.

50 We claim:

1. Mechanism for opening folded sheets, comprising inversely rotating sheet opening members, sheet conveying tapes and means associated with said tapes for presenting to said rotating sheet opening members a folded sheet with its edges oblique to the axis of rotation of said sheet opening members.

2. Mechanism for opening folded sheets, comprising folded-sheet opening members, sheet conveyor tapes associated with said members, means for positioning a folded sheet upon the tapes so that its edges are oblique to the longitudinal stretch of said tapes, and means for retaining the sheet in its oblique position during the travel of the conveyor tapes towards the sheet opening members.

3. Mechanism for opening folded sheets, comprising a folded-sheet opening device, sheet conveyor tapes associated with said device, and sheet stops adapted to extend in an oblique line across the path of movement of a folded-sheet carried by said tapes.

4. Mechanism for opening folded sheets, comprising folded-sheet opening members, sheet conveyor tapes associated with said members, sheet stops adapted to extend in an oblique line across the tapes to engage and deflect a folded sheet carried by the said tapes, and means for retaining the said sheet in the deflected position during its further conveyance to the sheet opening members.

5. Mechanism for opening folded sheets, comprising in combination, folded-sheet opening members, sheet conveyor tapes leading to said folded-sheet opening members, a series of sheet-registering stops movably mounted and adapted to project between the said tapes and extend in an oblique line transversely thereof, a pivotally mounted drop friction roll interacting with said

- sheet stops, sheet clamping tapes associated with said conveyor tapes and means for synchronizing the mechanical actuation of said sheet opening mechanism.
6. Mechanism for opening folded sheets, comprising in combination, inversely rotating sheet opening members, a series of sheet conveyor tapes adapted to move at right angles to the axis of rotation of said sheet opening members, a series of sheet stops pivotally mounted beneath said tapes and adapted to project at timed intervals between and above said tapes, at least one drop friction-roll pivotally mounted above said conveyor tapes and adapted to engage a sheet carried by said tapes, a lower friction roll beneath said tapes associated with each upper friction roll, a second series of conveyor tapes superimposed upon the upper stretches of the first mentioned tapes and adapted to engage and hold in position a sheet subsequent to the registration of the latter with the said sheet stops, and means for synchronizing the mechanical actuation of the said sheet opening mechanism.
10. A sheet handling machine, including in combination, a machine drive, a stack container for folded sheets, inversely rotating sheet-opening rolls, sheet conveyor tapes extending from said stack container to said sheet opening rolls, means for feeding a folded sheet from said stack container to said conveyor belts, sheet-stops pivotally mounted beneath said conveyor belts and extending transverse thereto in an oblique line, means for periodically projecting said stops into the path of the sheet carried by said conveyor tapes, sheet gripping rolls associated with said conveying belts, a second series of conveyor belts associated with said sheet-opening rolls and superimposed upon the upper stretches of the first sheet conveyor belts, and means for actuating from the machine drive the said sheet handling mechanism.
15. A method of opening a folded sheet or book-section, which comprises feeding the folded sheet to rotary sheet-opening means in such manner that the foremost edges of the sheet opposite its fold are seized by said sheet-opening means while lying at an angle to the axis of rotation of said sheet-opening means, the sheet edges thus being initially parted from one corner of said folded sheet.
20. A method of opening a folded sheet or book-section, which comprises feeding the folded sheet to inversely rotating sheet-opening members so that the foremost open edges of said sheet opposite its fold pass between said members at an angle to the axis of rotation of the latter, the sheet edges thus being initially parted from one corner of said folded sheet.
25. Means for opening folded sheets or book-sections, comprising a sheet-opening device, means for conveying a folded sheet to said sheet-opening device, and means associated with said conveying means for positioning said folded sheet with its edges oblique to the direction of its movement so that one corner of its open edges is initially engaged by said opening device.
30. Means for opening folded sheets or book-sections, comprising a rotary sheet-opening device, means for conveying the folded sheet to said sheet-opening device, and means associated with said sheet conveying means for presenting to said rotary sheet-opening device a folded sheet with its edges oblique to the axis of rotation of said sheet opening device.
35. Means for opening folded sheets or book-sections, comprising at least one pair of inversely rotating sheet-opening members, means for conveying a folded sheet to said sheet-opening members, and means for directing said sheet so that initially one corner of it is engaged by said sheet-opening members.
40. A method of opening a folded sheet or book-section comprising moving the folded sheet toward sheet-opening means with the edges opposite the fold forward and adjusting the position of the folded sheet while moving toward the sheet-opening means so that a corner of the folded sheet is first presented to the sheet-opening means.
45. Means for opening folded sheets or book-sections, comprising a sheet-opening device, sheet conveyor tapes adapted to convey the closed sheet towards said sheet-opening device, and means associated with said conveyor tapes for positioning said closed sheet with its edges oblique to the direction of movement of said conveyor tapes so that one corner of its open edges is initially engaged by said opening device.
50. Means for opening folded sheets or book-sections, comprising sheet-opening means, sheet-conveying means adapted to feed a closed sheet to said sheet-opening means, with the edges opposite the fold forward, and means for adjusting the position of the folded sheet during its conveyance by said sheet-conveying means so that a corner of the open edges of said sheet is first presented to said sheet-opening means.
55. Means for opening folded sheets or book-sections, comprising sheet-opening means, sheet conveyor tapes adapted to receive a closed sheet and feed the latter to said sheet opening means, with the edges opposite the fold forward, and means for adjusting the position of the folded sheet during its conveyance so that its forward open edge lies oblique to the longitudinal stretch of the tapes and one corner of the closed sheet is initially engaged by said sheet-opening means.
60. Means for opening folded sheets or book-sections, comprising at least two inversely rotating sheet-opening members, means for conveying a folded sheet to said members with the edges opposite the fold forward, and means for adjusting the position of the folded sheet as it moves towards said sheet-opening members so that its forward open edges lie oblique to the axes of said sheet-opening members to enable the latter to engage initially one corner of said folded sheet.
